UNITED STATES PATENT OFFICE.

WILHELM MAUCH AND WILHELM KOENIG, OF BRADDOCK, NORTH DAKOTA.

RAIL-JOINT ATTACHMENT.

1,111,395.

Specification of Letters Patent. Patented Sept. 22, 1914.

Application filed April 7, 1914. Serial No. 830,201.

To all whom it may concern:

Be it known that we, WILHELM MAUCH and WILHELM KOENIG, citizens of the United States, residing at Braddock, in the county 5 of Emmons and State of North Dakota, have invented certain new and useful Improvements in Rail-Joint Attachments; and we do hereby declare the following to be a full, clear, and exact description of the invention, 10 such as will enable others skilled in the art to which is appertains to make and use the same.

This invention relates broadly to new and useful improvements in railroad rail attachments which are designed to automatically tighten the bolts passing through the rail web and the rail joints.

The principal object of this invention contemplates the provision of a device of the 20 type described which shall be automatically actuated by the passing of a train over the joint in question to tighten the bolts of said joint.

A further object is to provide means 25 whereby this device will be actuated by the passing of a train over the joint and will yet remain unoperated by the passage of a hand car.

An object of equal importance to the foregoing is to provide a device of the character described which is constructed with such regard to proportion, number and arrangement of parts as to be cheaply manufactured, that will be durable and efficient in operation, 35 and can readily be applied to any standard or type of rail with a minimum expenditure of time and labor.

The above and additional objects will be accomplished by such means as are illustrated in the accompanying drawings, described in the following specification, and then more particularly pointed out in the claims, which are appended hereto and form 40 a part of this application.

With reference to the drawings wherein we have illustrated the preferred embodiment of our invention as reduced to practice and throughout the several views of which like characters of reference indicate corresponding parts, Figure 1 is a side elevation 45 of our device as applied to a rail joint, the parts of one of the burs being shown in section. Fig. 2 is a transverse section taken on the plane indicated by the line 2-2 of Fig.

1, and, Fig. 3 is an enlarged detail of the 55 bur as it appears in Fig. 2 with the rotatable casing removed.

Before taking up the description of the drawings, we desire to emphasize the fact that while the invention has been designed 60 with particular reference to the needs of railroad track maintenance, has been illustrated and will hereinafter be described in that connection, it may nevertheless be applied with equal efficiency to the rails of a 65 street railway or interurban line, or any other form of roadbed including rails and vehicles adapted to ride thereon.

Referring now to the drawings, it will be seen that our invention includes three main 70 elements, namely the bur, which is attached to the protruding end of the bolt, the movable plate adapted to tighten the bur by means hereinafter to be disclosed, and the standards adapted to be set outside of the rails one on 75 each side of the rail joint and in proximity thereto. Taking these elements up in the order named it will be seen that the bur designated as 1 is adapted to replace the ordinary variety of nut and is similarly threaded 80 on the protruding extremity of the bolt 2, which passes through the angle bars 3 and 4 and the rail web 5 of the rail, which is designated generally as 6.

This bur 1 seats against the ordinary 85 spring washer 7 and is constructed, as are the other portions of our device, from any cheap and durable metal such as cast iron or steel. It will be obvious therefore that the only element now composing the common rail joint which it is necessary to throw away will be the nut, all other parts of the 90 same being retained in their usual positions.

Taking up the peculiar construction of our bur more specifically, it will be seen that 95 it comprises an annular body portion 8 formed on either edge of which are the enlarged flanges 9 and 10 so that it may be considered as substantially U-shaped in cross section. In the center of the groove 100 thus provided by the upstanding flanges 9 and 10 is countersunk a ratchet wheel 11 formed integral with the rest of the bur, as is clearly shown in Fig. 3.

An annular casing 12, of such proportions 105 that it is adapted to lie within the groove 11' and between the flanges thereof, is movably mounted thereon. This casing 12 in-

cludes an extended lever arm 13, as shown in Fig. 1, and is also provided with a recess 14, in which the pawl 15 is pivotally mounted, as shown at 16. It will be obvious by a perusal of the parts shown in section in Fig. 5 1 that a downward movement of the lever extension 13 will result in the partial rotation of the bur 1, due to the engagement of the pawl 15 with the ratchet 11, and accordingly a tightening of the bur upon the bolt 2 is accomplished. This desired downward movement of the lever extension above referred to is accomplished by means contained in the second main element of our invention, namely the movable plate. This plate 17 is rectangular in cross section and of substantially the same proportions as shown in the drawings, being formed on its upper edge with a cut out portion, as shown in Fig. 2, which said portion serves a purpose to be herein-after more fully described. This plate 17 is so positioned as regards the rails that its broader surface rests against the outer side 25 of the rail head and that the line of the rail joint coincides in its own vertical center line, as shown in Fig. 1, and is provided at either extremity with the outstanding lugs 19, which are riveted or otherwise suitably secured, as shown at 20, to itself. The outer extremities of these lugs 19 are provided with enlarged washers 21, for a purpose to be afterward more clearly disclosed. The upper edge of this plate 17 is rounded 35 off at each terminal, as shown at 22, and its lower edge is provided with means 23' for forming a loose connection with the lever extension 13 of the casing 12.

We come now to the construction of the 40 third and last main element of our invention which coacts with the other two elements, above described, in accomplishing the purposes already set forth. This element comprises mainly the standard 23 inclined toward the rail and has formed at its lower extremity the angular flange 24, by which it is adapted to be secured to the tie by any suitable means, such as 25. The lower extremity of this standard 23 is likewise 45 formed with an angular portion 26 which extends parallel to the rail 6 and the plate 17 and is contiguous to the latter. The intermediate portion of this flange 26 is slotted, as shown at 27, and through these slots 50 the lugs 19 are adapted to extend, the washers 21 being positioned outwardly of the flange 26 and being of comparatively a large diameter as regards the slot, serve to keep the said lugs from becoming unseated. The 55 lower portion of this slot contains an up-standing pin 28 which holds in place on the lower end of the slot suitable resilient means, such as the spring 29. The upper end of the spring bears against the lug 19 and normally serves to hold it against the

upper portion of the slot 27, as is clearly shown in Fig. 2.

It will be obvious that according to the foregoing description, the operation of our device is as follows: The flange of the car 70 wheel in traveling along the rail comes in contact with the plate 17, such contact being rendered smooth and gradual by the rounded portions 22, and the weight of the car forces the plate 17 downwardly against 75 the tension of the spring 29. This vertically downward movement is translated through the lever extension 13 into a rotational movement which is imparted to the casing 12 in such manner that the pawl 15 80 is forced to actuate the ratchet 11 through a small arc, and this ratchet 11 being formed integral with the bur 1 as a whole, serves to tighten the bur upon the bolt 2 and forces it against the spring washer 7, thus accomplishing the purpose desired. 85

It will be noted the cut out portion 18 at the upper edge of the plate 17 is so formed that in the event of a hand car being used upon the track the narrower flange of the 90 car wheels will not engage the upper edge of the plate 17 and the device will accordingly not be actuated. This is done for the reason that a hand car would not have sufficient weight to overcome the tension of the spring 95 29 and would accordingly be derailed.

While in the foregoing we have illustrated in the drawings and described in the specification such combination and arrangement of elements as constitute the preferred embodiment of our invention, we desire to emphasize the fact that we may make such minor changes in the matters of proportion and degree, in later adaptations of our device as 100 shall not alter the spirit of our invention as 105 defined in the appended claims.

What we claim as new is:

1. In a device of the character described including a rail joint and bolts provided therefor, rotatable burs for the ends of said bolts, and means whereby said burs are rotated by the passage of a train. 110
2. In a device of the character described including a rail joint and bolts provided therefor, rotatable burs threaded on said bolts, lever arms connected to said burs, and means whereby said lever arms are depressed during the passage of a train. 115
3. In combination with a rail joint including angle bars and bolts provided therefor, of rotatable burs threaded on the ends of said bolts, a ratchet wheel formed integral with said burs, rotatable casings mounted upon said burs, lever arms formed integral with said casings, and means whereby said lever arms are adapted to be depressed during the passage of a train. 120
4. In a device of the character described the combination with a rail joint and bolts provided therefor; of burs threaded on the 125 130

ends of said bolts, a movable plate adapted to be depressed during the passage of a train, and means whereby the depression of said movable plate tightens the burs upon the bolts.

5. In a device of the character described the combination with a rail joint and bolts provided therefor; of burs threaded upon the ends of said bolts, a movable plate 10 adapted to be depressed during the passage of a train, means whereby said depression of said movable plate tightens the burs upon the bolts, and resilient means for returning said movable plate to its normal position 15 after the train has passed.

6. In a device of the character described including a rail joint and bolts provided therefor, burs threaded upon the ends of said bolts, standards positioned in proximity 20 to said rail joint, and a movable plate carried by said standards and adapted to

tighten the burs upon the bolts during the passage of a train.

7. In a device of the character described including a rail joint and bolts provided 25 therefor, rotatable burs for the ends of said bolts, and means for tightening said burs thereupon by the passage of a train.

8. The combination with a rail joint including angle bars and bolts provided therefor, of rotatable burs threaded upon said bolt, means for limiting the unthreading of said burs and means for tightening said burs automatically by the passage of a train.

In testimony whereof we have signed our 35 names to this specification in the presence of two subscribing witnesses.

WILHELM MAUCH.
WILHELM KOENIG.
